(57) **CLAIM**

The ornamental design for a folding knife, as shown and described.

DESCRIPTION

FIG. 1 is side view of a folding knife according to the invention having the blade folded into the handle;

FIG. 2 is a top view of the folding knife illustrated in FIG. 1;

FIG. 3 is an opposite side view of the folding knife illustrated in FIG. 1;

FIG. 4 is a bottom view of the folding knife illustrated in FIG. 1;

FIG. 5 is a right-side end view of the folding knife illustrated in FIG. 1;

FIG. 6 is a left-side end view of the folding knife illustrated in FIG. 1;

FIG. 7 is another side view of the folding knife illustrated in FIG. 1 having the blade in the extended position;

FIG. 8 is a bottom view of the folding knife illustrated in FIG. 7;

FIG. 9 is an opposite side view of the folding knife illustrated in FIG. 7;

FIG. 10 is a top view of the folding knife illustrated in FIG. 7;

FIG. 11 is a left-side view of the folding knife illustrated in FIG. 7;

FIG. 12 is a left-side view of the folding knife illustrated in FIG. 9; and,

FIG. 13 is a close-up view of the pivot point of the folding knife illustrated in FIG. 8.

UNITED STATES PATENT AND TRADEMARK OFFICE
CERTIFICATE OF CORRECTION

PATENT NO. : Des. 505,057 S
APPLICATION NO. : 29/208375
DATED : May 17, 2005
INVENTOR(S) : Darrel Ralph

Page 1 of 1

It is certified that error appears in the above-identified patent and that said Letters Patent is hereby corrected as shown below:

On the cover page at Section (75), The spelling of the inventor's name "Darryl Ralph" is to be corrected to read --Darrel Ralph--.

Signed and Sealed this

Sixteenth Day of October, 2007

A handwritten signature in black ink, appearing to read "Jon W. Dudas". The signature is written in a cursive style with a large, stylized "J" and "W".
